UNITED STATES PATENT OFFICE.

LEWIS L. TATUM, OF MILWAUKEE, WISCONSIN, ASSIGNOR TO THE CUTLER-HAMMER MFG. CO., OF MILWAUKEE, WISCONSIN, A CORPORATION OF WISCONSIN.

CIRCUIT-CONTROLLER.

1,138,808.

Specification of Letters Patent. Patented May 11, 1915.

Application filed June 13, 1913. Serial No. 773,574.

To all whom it may concern:

Be it known that I, LEWIS L. TATUM, a citizen of the United States, residing at Milwaukee, in the county of Milwaukee and 5 State of Wisconsin, have invented new and useful Improvements in Circuit-Controllers, of which the following is a full, clear, concise, and exact description, reference being had to the accompanying drawing, forming 10 a part of this specification.

My invention relates to improvements in circuit controllers and is particularly applicable to rheostats and other controllers designed to successively establish different 15 electrical circuits. Heretofore two distinct types of controllers have been employed for such purposes; namely "sliding contact" controllers and "abutment contact" controllers. It has been found in practice, how- 20 ever, that each of these types, while possessing certain advantages, has also certain objectionable features.

My invention has among its objects to provide a controller which will embody the ad- 25 vantageous features of both the sliding and abutment contact controllers and which, at the same time, will materially overcome the usual disadvantages of each.

Another object is to provide a simple, 30 durable and efficient controller which will operate both as a sliding contact and abutment contact controller.

A further object is to provide such a controller which operates with a positive abut- 35 ment movement prior to sliding movement in either direction.

Other objects and advantages of my in- 40 vention will hereinafter appear.

For the purpose of more fully and clearly 45 disclosing the nature and advantages of my invention I shall describe the embodiment thereof illustrated in the accompanying drawing, it being understood that the invention is susceptible of modification in other forms.

In the accompanying drawing, Figure 1 is a front elevation of the controller; Fig. 2 is an enlarged perspective view of the controller arm; and Fig. 3 is an enlarged side 50 elevation of a part of Fig. 1.

The controller illustrated is of the sole- 55 noid operated type and particularly adapted to use as a rheostat. It includes a series of

contacts 1 mounted upon a suitable support- 60 ing panel 2, a coöperating contact 3 and a solenoid 4 for operating said contact 3 through the medium of its plunger 5 and a double pivoted arm.

The double pivoted arm comprises two sec- 65 tions 6 and 7. The section 6 is fulcrumed upon a stud 8 projecting from the panel 2. The section 7 carries the contact 3 and is swiveled to the section 6. The arm moves about the pivot 8 to slide the contact 3 over the contacts 1 while the swivel connection 70 between the sections 6 and 7 permits move- 65 ment of the contact 3 substantially at right angles to its plane of sliding movement. This provides for both sliding and abutment 70 movement of the contact 3 relative to the contacts 1.

The swivel connection between the sections 6 and 7 may be of any preferred form. As 75 illustrated, the section 7 is provided at one end with a transverse yoke 10 which is swiveled upon a spindle 11 projecting from 80 the end of the section 6. The spindle is shown as comprising a screw threaded into the section 6. The spindle 11, it will be noted, extends substantially at right angles 80 to the pin forming the pivot of the section 6. The section 7 of the arm and contact 3 have a pivotal movement about the spindle 11 to the extent illustrated in dotted and full 85 lines, Fig. 3. The full lines show the sec- 90 tion 7 in a position to cause engagement of contact 3 with contacts 1, while the dotted lines show the arm in a position to separate the contact 3 from the contacts 1. The move- 90 ment of the contact 3 away from the contacts 1 is limited by a stop 12 on the yoke 10 which engages a coöperating stop 13 on the section 6 of the arm. The dotted line position of the section 7 of the arm is the normal 95 position thereof.

The solenoid 4, through its plunger, 100 serves to rotate the contact 3 on both of its pivots 11 and 8. To this end its plunger 5 is connected by a suitable device 15 to a cross-pin 16 carried by the yoke 10 of the section 7. Further, means are provided to cause movement of the solenoid plunger in either direction to rock the contact 3 on its pivot 11 prior to rocking the same upon its pivot 8. This means comprises a dash-pot 105 17 and a counter-balance 19 both opera-

tively connected to the section 6 of the contact-carrying arm.

The dash-pot 17 opposes the upward movement of the section 6 and in so doing performs a triple function: First, assuming that the contact 3 is in the dotted line position, shown in Fig. 3, it resists the operation of section 6 until the section 7 and contact 3 are first thrown into the position shown in full lines, Fig. 3. Second, it retards the upward movement of the contact 3 over the contacts 1. Third, its drag or counter-pressure on the section 6 of the contact-carrying arm results in firmly pressing the contact 3 against the contacts 1 during the sliding movement of the latter until section 6 abuts a resilient stop 18.

The resilient stop 18 is arranged to be engaged and compressed in the final position of the contact 3 and under such conditions maintains the desired pressure between the contact 3 and the contacts 1 when the controller comes to rest and the dash-pot becomes inert.

25 The counter-balance 19 upon the return movement of the solenoid plunger tends to perform the first above-described function of the dash-pot 17 when the controller arm is raised. It tends to maintain the section 6 of the contact carrying arm in elevated position and thereby tends to resist the descent of said section until the contact 3 is first rocked on its pivot 11 by the weight of the solenoid plunger.

30 The operation of the controller, as will now be obvious, is as follows: Assume that the contact carrying arm is in the position shown in Fig. 1 and that the section 7 of said arm and the contact 3 are in the dotted line position, Fig. 3. If now the solenoid 4 be energized it will attract its plunger 5 thereby exerting a pull on the section 7 of the contact-carrying arm eccentric to its pivot 11. Under these conditions, the section 7 is free to rock on its pivot 11 while the dash-pot 17 opposes movement of the section 6 about its pivot. Accordingly the initial movement of the solenoid plunger will forcibly throw the contact 3 into abutment engagement with the lowermost contact 1. Continued movement of the solenoid plunger will then move both sections 6 and 7 of the controller arm upwardly, thereby sliding the contact 3 over the contacts 1 successively. The counter-pressure of the dash-pot maintains the contact 3 in firm engagement with the contacts 1 during the aforesaid operation, while the resilient stop 18 maintains the desired pressure between the contacts after the controller has been brought to rest. Assume now that the controller has been fully operated and that the solenoid is deenergized. Again the section 7 of the contact carrying arm is free to rock upon its pivot 11 while the descent

of the arm 6 is opposed by the counter-balance 19. Accordingly, the weight of the solenoid plunger when released first carries the contact 3 outwardly out of engagement with the contact 1, thereby breaking circuit in 70 the same manner as an abutment contact controller. Thereafter the weight of the solenoid plunger carries both sections of the contact carrying arm downwardly, maintaining the contact 3 out of engagement 75 with the contacts 1 throughout the descent of said arm.

It will thus be observed that the contact 3 is operated as an abutment contact prior to sliding movement in either direction and 80 that its abutment movement is accomplished with a quick action.

What I claim as new and desire to secure by Letters Patent is:

1. In a circuit controller, in combination, 85 a contact, a support therefor, and means for operating said support to impart both an abutment and sliding movement to said contact, said means being mechanically connected to said support to inherently tend 90 to render said movements of said contact progressive.

2. In a circuit controller, in combination, 95 a contact, a support therefor and means for operating said support to impart both an abutment and sliding movement to said contact, said means being mechanically connected to said support to inherently tend 100 to effect abutment movement of said contact prior to sliding movement thereof in either direction.

3. In a circuit controller, in combination, 105 a plurality of stationary contacts, a coöperating movable contact operable with respect to certain of said stationary contacts 110 as an abutment contact and with respect to others as a sliding contact and operating means for said movable contact inherently tending to effect said movements progressively.

4. In a circuit controller, in combination, 115 a series of stationary contacts, a coöperating movable contact operable as an abutment contact with respect to the end contacts of said series and as a sliding contact 120 with respect to the intermediate contacts of said series and operating means for said contact including mechanical means inherently tending to render said movements of said contact progressive with the abutment movement preceding the sliding movement.

5. In a circuit controller, in combination, 125 a contact movable both as an abutment contact and as a sliding contact and operating means for said contact including mechanical means inherently tending to render said movements of said contact progressive with the abutment movement preceding the sliding movement in both directions.

6. In a circuit controller, in combination,

- a contact having both abutment and sliding movements and a single electromagnetic device inherently tending to effect said movements of said contact progressively with its abutment movement preceding its sliding movement.
7. In a circuit controller, in combination, a contact movable both as a sliding and abutment contact and means opposing the sliding movement of said contact to cause the same to first move as an abutment contact when subjected to an operating force.
8. In a circuit controller, in combination, a contact movable both as a sliding contact and as an abutment contact and means opposing the sliding movement of said contact in both directions to cause the same to first move as an abutment contact when subjected to an operating force.
9. In a circuit controller, in combination, a contact movable both as a sliding contact and as an abutment contact and a dash-pot opposing the sliding movement of said contact to cause it to first operate as an abutment contact.
10. In a circuit controller, in combination, a series of stationary contacts, a coöperating movable contact member operable with respect to said stationary contacts both as a sliding contact and an abutment contact and means opposing the sliding movement of said movable contact to cause it to first operate as an abutment contact and to forcibly hold the same in engagement with said stationary contacts during its sliding movement.
11. In a circuit controller, in combination, a contact movable both as an abutment contact and as a sliding contact, stationary contacts to be engaged thereby, a dash-pot opposing the sliding movement of said movable contact to cause the same to first operate as an abutment contact and to forcibly hold the same in engagement with said stationary contacts during its sliding movement.
12. In a circuit controller, in combination, a contact movable both as an abutment contact and as a sliding contact, stationary contacts to be engaged thereby, a dash pot opposing the sliding movement of said movable contact to cause the same to first operate as an abutment contact and to forcibly hold the same in engagement with said stationary contact during its sliding movement and means for maintaining said forcible engagement when said movable contact is brought to rest.
13. In a circuit controller, in combination, a contact having two pivotal movements, one for sliding contact operation and the other for abutment contact operation and an operating member connected to said contact to inherently tend to first impart the latter pivotal movement thereto.
14. In a circuit controller, in combination, a series of stationary contacts, a coöperating movable contact operable as an abutment contact with respect to the end contacts of said series and as a sliding contact with respect to the intermediate contacts of said series and an operating member movable in a single direction to effect both movements of said movable member.
15. In a circuit controller, in combination, a contact movable as an abutment contact and as a sliding contact and an operating member movable in a single direction to affect both of said movements of said contacts successively and in an opposite direction to again affect both movements of said contacts successively.
16. In a circuit controller, in combination, a pivoted arm, a contact support pivoted to said arm, a contact secured to said support, said contact being movable on the pivot of said support as an abutment contact and on the pivot of said arm as a sliding contact and an operating member for said support and said arm connected to the former to inherently tend to first operate said contact as an abutment contact.
17. In a circuit controller, in combination, a pivoted arm, a contact support pivoted to said arm, a contact secured to said support, said contact being movable on the pivot of said support as an abutment contact and on the pivot of said arm as a sliding contact and an operating member for said support and said arm connected to the former to inherently tend to first operate said contact as an abutment contact, and means retarding the movement of said arm to insure the said sequence of operation.
18. In a circuit controller, in combination, a pivoted arm, a contact support pivoted to said arm, a contact on said support, said contact being movable as an abutment contact on the pivot of said support and as a sliding contact on the pivot of said arm and an operating solenoid having its plunger connected to said contact support to affect both of said movements of said contact.
19. In a circuit controller, in combination, a pivoted arm, a contact support pivoted to said arm, a contact on said support, said contact being movable as an abutment contact on the pivot of said support and as a sliding contact on the pivot of said arm and an operating solenoid having its plunger connected to said contact support to affect both of said movements of said contact, and means for retarding the movement of said arm to cause said contact to be first operated as an abutment contact.
20. In a circuit controller, in combination, a pivot arm, a contact support pivoted thereto, a contact on said support, said contact being movable as an abutment contact on the pivot of said support and as a sliding con-

tact on the pivot of said arm, an operating solenoid having its plunger connected to said contact support, a dash-pot connected to said arm and limiting means for said arm.

5 In witness whereof, I have hereunto sub-

scribed my name in the presence of two witnesses.
